UNITED STATES PATENT OFFICE.

LORNE A. GRIFFIN, OF EVANSTON, ILLINOIS, ASSIGNOR TO CONVEYORS CORPORATION OF AMERICA, OF CHICAGO, ILLINOIS, A CORPORATION OF NEW YORK.

ASH CONVEYER.

Application filed June 10, 1921, Serial No. 476,442. Renewed November 22, 1922.

To all whom it may concern:

Be it known that I, LORNE A. GRIFFIN, a citizen of the United States, and resident of Evanston, in the county of Cook and State 5 of Illinois, have invented a certain new and useful Improvement in Ash Conveyers, of which the following is a full, clear, concise, and exact description, reference being had to the accompanying drawings, forming 10 a part of this specification.

My invention relates to ash conveyers, and, briefly stated, the principal objects of my invention are as follows:

1. The provision of an ash conveyer
15 which, in part, consists in the combination
and rearrangement of parts heretofore used
in two distinctly different types of ash con-
veyer, the new arrangement possessing all
of the advantages of each of said prior types,
20 possessing additional advantages not to be
found in either of the prior types, and
eliminating certain disadvantages which
heretofore have been regarded as inherent
in one or the other of the aforesaid prior
25 types of ash conveyer.

20 types of ash conveyer.
2. The provision of an ash conveyer wherein there is no danger of fire or explosion in the ash tank, despite the fact that the tank is of the type wherein a pressure
30 less than atmospheric is maintained when the conveyer is in operation.

3. The provision of an ash conveyer in which it is feasible to use right angle elbows in the conveyer pipe line, despite the fact that the travel of the ashes along the longitudinal and vertical portions of the conveyer conduit is produced by suction in the ash tank.

4. The provision of an ash conveyer
40 wherein the inevitable abrasion of the con-
veyer conduit by the ashes is reduced to a
minimum.

5. The provision of an ash conveyer wherein I avoid noise at the hoppers, an objection inherent in certain types of ash conveyers.

6. The provision of an ash conveyer wherein dust-laden steam and air is forcibly discharged from the ash tank, and is thoroughly cleaned before being permitted to escape to the atmosphere.

In the accompanying drawing, illustrating my invention, as 1 and 2 I have illustrated the horizontal portions of the conveyor conduit, and at 3 the riser which con-

nects said horizontal portions and affords communication between them. The horizontal portion 1 of the conduit is provided with a plurality of hoppers 4—4, each of which is located in front of a fire box door, 60 diagrammatically indicated at 5—5. Each hopper, when not in use, is closed by the usual cover or hopper plug (not shown). The riser is connected with the horizontal portions of the conveyer conduit by right 65 angle elbows 6 and 7.

The upper horizontal portion of the conveyor conduit discharges into the ash tank 8, which, if desired, may be provided with the customary baffle 9. Tank 8 is conveniently supported above the track 10 by the framework 11. The tank here shown is of the tapering bottom type and is provided with a discharge gate 12. The tank is as nearly air-tight as it is practically feasible to make it. It is extremely difficult, if not impossible, to make the tank absolutely air-tight at some points, particularly at the discharge gate, but as will presently appear, my present invention contemplates a certain amount of air leakage into the tank, and provides means whereby to prevent any undesirable result by reason of this leakage. 70 75 80

Connected with the upper end of the tank is an aspirator 14, herein shown as comprising the T fitting 14^a, the venturi, or choke tube 14^b, and the steam nozzle 14^c. The venturi, or choke tube, discharges into the separator 15, which is supported adjacent the ash tank in any convenient manner, as, for instance, by the supporting framework 16. The separator consists of a suitable chamber wherein are disposed a plurality of baffles 17, 18, and 19, which cause the steam and air discharged into the separator by the aspirator to take a winding path, as indicated by the arrows. Disposed within the separator are a plurality of spray pipes 20—20, which serve to wash the entrained ash dust from the steam and air as the same passes through the separator. It will be noted that the spray pipes are preferably so located that the steam and air passing through the separator is caused to pass through a curtain of water spray at a plurality of points in the path of travel thereof, through the separator. Pipes 21—21 serve to drain the water and ash dust from the separator. It will be understood that the separator not only serves to clean the air and

steam discharged from the tank by the aspirator, but it also serves as a muffler to silence the operation of the aspirator.

Projecting into each of the right angle 5 elbows 6 and 7 is a steam nozzle 22, each of these nozzles discharging in the line of travel of the ashes through the conveyer conduit. A valve 23 controls the supply of steam from the steam supply pipe 24 to the 10 nozzles 22, and also controls the supply of steam to the aspirator nozzle 14°. It will be understood that opening of the valve 23 causes simultaneous operation of the elbow nozzles 22—22, and the aspirator nozzle 14°.

15 It is the partial vacuum created in the ash tank 8 by the aspirator 14 which is relied upon to convey ashes from the hopper 4—4 through the portions 1, 3 and 2 of the ash conveyer conduit. I am not the first to provide an ash conveyer system comprising an ash conveyer conduit in combination with an ash receptacle from which air is exhausted by a fan, or other equivalent means. 20 However, all of the systems of this general 25 type heretofore proposed have been subject to certain serious objections. One of the principal objections to this type of system has been the fact that it has been impossible to make sharp turns in the conveyer conduit. For this reason, it has heretofore not been feasible to use this type of system in many installations. My present invention overcomes this serious objection to the type 30 of system wherein travel of the ashes 35 through the conveyer is caused by suction created in the ash tank. The elbow nozzles 22—22 serve effectively to assist the conveyed ashes around the sharp turns at the right angle elbows. These nozzles 22—22

40 however, are of such capacity that while they do assist the conveyed ashes around the elbows they do not impart any considerable degree of momentum to the conveyed ashes, as the same pass the elbows. By reason 45 son of this arrangement, abrasion of the conduit at points just beyond the elbows in the line of travel is minimized.

Another serious objection to the type of ash conveyer wherein a partial vacuum is 50 maintained in the ash tank, has been the fact that air leaking into the tank, particularly through the discharge gate, has affected the hot cinders in the tank, as does the air in a forge. The combustion of cinders, etc., in the ash tank due to a forced

60 draft therethrough is apt to result very seriously; dangerous gases are created, and, in some cases, the ash tank has been known to be blown to pieces by the gas pressure created therein. This difficulty is eliminated in the system of my invention, for the reason that the elbow nozzles 22—22 65 serve to saturate the conveyed ashes with steam, and thus thoroughly extinguish any fires in the ashes and cinders before the latter are deposited in the ash tank.

65 The fact that the elbow nozzles 22—22 of the present system need only be of capacity such that they will moisten the ashes, and assist the same around the elbows, enables 70 me greatly to reduce the noise at the hoppers, which, in a steam jet ash conveyer system, is always present, due to the operation of the steam nozzles.

75 In order properly to perform their functions in my present system, the nozzles 22—22 may be of a capacity such that they cause no considerable noise at the hopper.

Having thus described my invention, what I claim is new and desire to secure 80 by Letters Patent of the United States is:

1. An ash conveyer comprising a closed ash tank, an aspirator connected with the tank and arranged when operated to cause a partial vacuum therein, an ash conveyer 85 conduit terminating in the tank, said conduit comprising portions at right angles connected by elbows, steam nozzles at the elbows arranged to discharge sufficient steam into the conduit at the elbows to assist the conveyed ashes around the elbows, and means for applying steam to said nozzles and said aspirator.

90 2. In an ash conveyer system a closed ash tank, a conveyer conduit terminating within the tank, a separator disposed adjacent to the tank and a steam aspirator having the suction end thereof connected with the tank and its pressure end discharging into the separator, a partial vacuum created in the ash tank by the operation of the aspirator serving to cause the conveyed ashes to travel through the conduit to the ash tank.

95 In witness whereof, I hereunto subscribe 100 my name this 2nd day of June, 1921.

LORNE A. GRIFFIN.
